UNITED STATES PATENT OFFICE.

RAY HOWARD REED, OF KLAMATH FALLS, OREGON.

STOCK CARD.

Application filed September 3, 1921. Serial No. 498,537.

To all whom it may concern:

Be it known that I, RAY HOWARD REED, a citizen of the United States, and a resident of Klamath Falls, in the county of Klamath and State of Oregon, have invented 5 certain new and useful Improvements in Stock Cards, of which the following is a full, clear, and exact description.

This invention relates to stock cards having 10 novel means to indicate the exact quantity of stock on hand.

A stock record card constructed in accordance with this invention is provided with means to indicate the movement of the stock 15 and to indicate the exact quantity of stock on hand so as to prevent over and under-buying. Further a feature of the invention is the fact that the stock card indicates the correct location of the stock so that verification 20 may be made at any time by a person not thoroughly acquainted in the stock room.

The improved card is generally designated by the numeral 5 and may be of any 25 suitable size and is provided at the upper left hand corner with a line 6 indicating the block number of the stock, and in this case it may be assumed that the block stock is indicated by the letter A. A line 7 im- 30 mediately below the block or section number indicates the shelf number in the section A and in this case it will be seen that the stock is arranged on shelf number 4, and in bin No. 7 as indicated on the line 8 im- 35 mediately below the shelf number. By reference to the card the exact section, shelf and bin in which the stock is arranged may be located by anyone not familiar with the location of the various articles.

40 Directly beneath the designating means 6, 7 and 8 a line 9 is provided on which may be indicated the maximum quantity of articles to be carried in stock, and directly beneath this line 9 a line 10 is provided on 45 which may be written the minimum quantity of stock to be carried. Therefore, by referring to the designations on the lines 9 and 10 the stock clerk or other authorized individual may instantly ascertain the maximum and minimum quantities of stock to 50 be carried. Further, by reference to the balance column as will be hereinafter more fully described, the stock clerk may compare the quantity on hand with the minimum and maximum quantities to be carried.

55 At approximately the center of the card

the same is provided with a line 12 on which the name of the stock to be carried is indicated and directly beneath the line 12 is a line 14 on which the size of the article is indicated. Also beneath the line 14 is provided a line 16 on which the type of the article may be indicated.

At the right of the card or more specifically, at the upper right hand corner of the same, the catalogue number is written on a line 20, the firm from whom the article was purchased written on the line 21 and the factory cost written on the line 22. The landed or delivered cost is written on the line 23, the selling price to the jobbers on the line 24, the selling price to the dealers on the line 26 and the selling price retailed on the line 27.

It will be seen that all of the data pertaining to a particular article will be written on the same card so that it will not at any time be necessary to refer to the catalogues or various price lists to ascertain the data indicated on lines 20 to 27 80 inclusive. Also discount lists are not necessarily employed since the price of the various buyers is plainly indicated on the card.

At the left hand part of the card directly beneath the various lines is provided a column 28 in which is written the order number and in the column 30 is written the date on which the order was given. At the right of the column 28 is provided a column 90 31 in which the quantity ordered is written. At the right of the column 28 is provided a "Received" column 33 and on the opposite sides of this column date and quantity columns 34 and 35 are provided. 95

When the goods is ordered a notation of this is made in the column 28 and when the goods is received a notation of its receipt is made in the column 33.

A pair of columns 35' are arranged at 100 the right of the "Received" column and are provided with divisions 36 in which is written the date and with divisions 37 in which is written the price. At the right of each column 37 there is provided a balance 105 column 38 in which is written the exact quantity of goods on hand.

In the use of the improved record card the first step is to take a thorough inventory indicating the quantity, location, size or 110 type, catalogue number, factory cost, landed cost, jobber's, dealer's and selling price, the

name of the manufacturer or other from whom the goods were purchased and if possible the date ordered. The number order on which the goods were ordered, the date received, the manufacturer's invoice number, and on the first line in the "Sold" column, the quantity of goods on hand originally. This will show the date the inventory was taken and the balance on hand 10 on that date.

As the goods are disposed of, a notation of this fact is made on the sold side of the card and the balance is then indicated on the card so that the stock clerk and other interested parties may ascertain the exact 15 quantity of a given article on hand.

In carrying out the invention it is essential to correctly list the name of the goods on the card as there may be goods 20 of various descriptions on hand, which goods are of the same general type.

The incoming invoices for goods received are posted directly to the cards and prop-

erly checked and placed in their respective bins or shelves. When an order is given 25 for stock a notation of this is made immediately upon the card at the place indicated.

The stock may be checked periodically, and when the system is employed correctly 30 the stock may be kept at the proper point at all times.

I claim:

An individual stock card comprising a sheet having lines upon which the location 35 of and the maximum and minimum number of articles to be carried in stock is indicated, there being a plurality of vertical columns upon which the date of order and the date of its receipt is written, additional 40 columns indicating the date on which the articles are disposed of and in what quantities and for what price, and vertical columns indicating the balance of the articles on hand.

RAY HOWARD REED.
